Attorney.

UNITED STATES PATENT OFFICE.

KENNETH B. HASTINGS, OF BOSTON, MASSACHUSETTS.

SOUND-AMPLIFIER.

Specification of Letters Patent. Patented Nov. 13, 1917.

1,246,594.

Application filed March 10, 1917. Serial No. 153,985.

To all whom it may concern:

Be it known that I, KENNETH B. HASTINGS, a citizen of the United States, and resident of Boston, in the county of Suffolk and State of Massachusetts, have invented an Improvement in Sound-Amplifiers, of which the following description, in connection with the accompanying drawings, is a specification, like letters on the drawings representing like parts.

My present invention is an improved sound accelerator for use in telephone transmitters. The object of the invention is to improve and perfect sound concentrating or focusing apparatus for use in connection with telephone instruments employed in aiding hearing, especially such as are portable and carried by the user. In the manufacture of this type of hearing aids it is extremely important that any sound amplifying device which is employed, shall be very compact, light, attractive, and unobtrusive in appearance, because of the well-known sensitiveness of deaf or partially deaf persons to their affliction.

Heretofore it has been attempted to make sound concentrating devices for such telephone transmitters with some sort of encircling shell or resonators, to conduct the sound waves onto the diaphragm of the transmitter. Such prior devices, however, afforded very little increase in efficiency and all of the same required the telephone diaphragm and transmitter to be in a position opening away from the direction of the sound waves. Furthermore, these prior devices depended upon a substantially rigid construction which tended to deaden or dissipate the sound waves while the same were being focused. Also a further difficulty was that such prior devices admitted extraneous and objectionable noises to a large degree. In my present device I have provided an improved arrangement of a plurality of accelerators to concentrate, conduct and increase the action of the sound waves while leading the same onto the center of the transmitter diaphragm. These accelerators are preferably so sustained as to permit a considerable vibration or "spring" which, in use, actually increases in a clear and sharp manner, the action of the sound waves. I also find that the usual extraneous and objectionable noises or rumbles are largely eliminated in the use of my amplifier. I account for this remarkable phe-

nomenon because of the fact that the direct sound waves are considerably increased as they are led from one resonator or concentrator to another, thus actually seeming to increase the spoken words which constitute the main sound waves. The vibration of the bell also clarifies the tone and dissipates the outside noises.

Referring to the drawings illustrating preferred embodiments of the invention,

Figure 1 is a rear plan view of my amplifying transmitter; and

Fig. 2 is a cross sectional view of the same.

In the accompanying drawings I have illustrated a plurality of three sound concentrating devices, although the invention is fully carried out with a plurality of two such concentrating devices, and therefore I will first describe the transmitter as though fitted with the two sound deflectors, the addition of the third being a modification, which will be described later.

The apparatus includes a transmitter, 80 designated generally at 1, and shown in substantially conventional form with the diaphragm 2 thereon, carried by the box 3, to which is attached the cover 4 in usual manner, having an opening 5 therethrough arranged centrally over the diaphragm 2. In the drawing the usual molecular packing under the diaphragm 2 is omitted. Attached to the back of the box 3 is a flange member 6 with its flange 7 spaced slightly from the sides of the box 3 and carrying a second flaring flange 8 which extends considerably above and beyond the cover 4 and of considerably greater diameter than the first flange 7. I prefer to unite the flanges 8 and 7 substantially as shown in Fig. 2 with a rounded sound deflecting portion 9. Attached to the rim of the outer flange portion 8 is a thin plate 10 having a down-turned edge 11 arranged to fit over the rim 9 of the flange 8. This plate also has a plurality of perforations, preferably as indicated at 12 and 13. This plate is somewhat yielding and on its inner surface carries a bell-shaped member 14, which latter is of suitable diameter and extent whereby the rim 15 will extend over and slightly down into the slightly rounded portion 9 between the inner flange 7 and outer flange 8 of the member 6. The apparatus as thus described when employed only with the flange 8 and bell 14 is attached to the wearer or

carried by the suspension ring 16 attached to the back of the apparatus. In this position the diaphragm 2 faces the direction of the sound, which enters through the series 5 of perforations 12 and 13, impinges against the walls of the grooves 9 and from thence is deflected into the inner wall of the bell-shaped member 14, reverberating backwardly and forwardly between the same and 10 the cover 4 until reaching the opening 5. The bell member 14 being secured to the center of the plate 10 by the screw 16, permits both said plate and the bell member to vibrate somewhat and to act as a sounding 15 board amplifying, concentrating and focusing the sound waves through the central opening 5 and onto the diaphragm, and also clarifying the tone through the vibration of the bell member itself. Thus two distinct 20 vibrations are secured, one through the vibration of the plate holding the bell and the other through the vibratory properties of the bell member itself.

The apparatus enables a clear, sharp amplification of the sound waves to be directed onto the transmitter diaphragm, while the construction actually eliminates the objectionable rumbling noises through the action of the bell as explained above. The series 25 of perforations around the front of the plate 10 further accentuate the vibratory action of the plate and bell, thus increasing the sounding board effect.

If desired, an additional concentrator 30 may be employed, such as the cupshaped member 17, having its central portion 18 contacting with the plate 10 within the series of perforations and also secured thereto by the screw 16, and the outer rim of said 35 member 17 extending as an encircling shell 19 overlapping and covering the flange 8, said shell having a curved peripheral form as illustrated at 20. With this additional 40 attachment, the sound waves, collecting and entering between the rim 19 and flange 8, are thrown by the curved wall 20 through the perforations 12 and 13 and thence onwardly to the transmitter 2 as has been described. With this additional magnifying 45 attachment, the instrument may be carried or worn by the user in the same position as before, although I prefer to have the attachment 17 opening outwardly, and for this purpose would remove the suspending ring 50 15 and attach a similar ring 20 to the upper part of the cup-shaped member 17. In either case the wires 21 and 22 could be led as shown in the drawings.

My amplifying and clarifying combination, either with or without the attachment 55 17, gives a simple, efficient and compact apparatus, which is arranged to receive, conduct, amplify and clarify, as well as focus, the sound waves, upon the central portion of 60 the transmitter diaphragm. The elasticity

and vibratory properties of the sound conducting flanges and members aids very materially in magnifying the action of the sounds upon the diaphragm of the transmitter. Furthermore, I find that the action 70 of the transmitter brings out the sound waves with a clear, sharp and well defined tone, while almost entirely eliminating objectional noises. In fact, the magnifying and sharpness is so pronounced that I may 75 employ advantageously a much smaller diaphragm than has heretofore been believed possible, thereby increasing the sharpness of the tones transmitted and enabling the entire apparatus to be compact and unobtrusive, as well as attractive in appearance. 80

My invention is further described and defined in the form of claims as follows:

1. Apparatus for amplifying sound, consisting in the combination of a telephone 85 transmitter, a cover therefor having a central opening for the transmitter diaphragm, a surrounding flange-like member, of greater diameter than the transmitter, and extending forwardly thereof, having sound deflecting walls, a plate carried by the flange-like member, and provided with a plurality of openings around its periphery, said plate having a central bell-shaped member overlapping the transmitter cover, whereby 90 sound waves entering said perforations are deflected by the flange-like member to the bell-shaped member and from thence to the transmitter.

2. Apparatus for amplifying sound and 100 focusing the sound waves upon the center of a telephone transmitter, comprising a transmitter, an encircling flange-like member extending forwardly of the transmitter, a plate carried by said flange-like member, 105 openings through said plate within the diameter of the flange-like member, and bell-shaped member attached to the inner surface of the plate and opening toward the transmitter, said plate and bell-shaped member 110 having a capacity for vibration whereby said waves entering said perforations are deflected, concentrated and focused upon the telephone transmitter.

3. Apparatus for amplifying sound and 115 focusing the sound waves upon the center of a telephone transmitter, comprising a transmitter, an encircling flange-like member extending forwardly of the transmitter, a plate carried by said flange-like member, 120 openings through said plate within the diameter of the flange-like member, and a bell-shaped member attached to the inner surface of the plate and opening toward the transmitter, said plate and bell-shaped member 125 having a capacity for vibration, in combination with a concentrating attachment also carried by the said perforated plate, which attachment overlaps and is of greater diameter than said flanged member, where- 130

by a plurality of sound concentrating members are provided.

4. Apparatus for amplifying sound and simultaneously clarifying the tone and focusing the sound waves upon a telephone transmitter, comprising the transmitter, and a flange-like member substantially encircling the transmitter, a bell-shaped member coöperating with said flange-like member and a vibratory support for said bell-shaped member.

5. Apparatus for amplifying sound and simultaneously clarifying the tone and focusing the sound waves upon the center of a telephone transmitter, comprising the

combination of the transmitter, a bell-shaped member positioned in front of said transmitter, a yielding support for the bell-shaped member united to said transmitter and a plurality of amplifying and concentrating devices coöperating with said bell-shaped member to conduct sound waves to the transmitter. 20

In testimony whereof, I have signed my name to this specification, in the presence of 25 two subscribing witnesses.

KENNETH B. HASTINGS.
